UNITED STATES PATENT OFFICE.

WALTER VILLA GILBERT, OF WESTMINSTER, LONDON, ENGLAND, ASSIGNOR TO GILBERT'S PATENTS LIMITED, OF LONDON, ENGLAND, A COMPANY.

IMPLEMENT FOR EFFECTING THE RELATIVE MOVEMENT OF TWO ELEMENTS.

Original application filed June 7, 1926, Serial No. 114,342, and in Great Britain February 25, 1926. Divided and this application filed January 22, 1927. Serial No. 162,901.

This invention relates to implements for use in effecting the movement with respect to one another of two projections, pins or sockets, such as is required to rotate one element relatively to another through a small angle as in attaching and detaching the removable tyre carrying portion of a road vehicle wheel.

This application constitutes a division of my co-pending application for Letters Patent on detachable wheel mechanism, filed June 7, 1926, and bearing Serial Number 114,342.

The present invention comprises an eccentric sheave provided with a hand lever and carrying an eccentrically placed projection, pin or socket for engaging one of the elements to be moved relatively to the other, the eccentric sheave being provided with a connecting link in the form of a strap member carrying an eccentrically placed projection, pin or socket for engaging the other of the relatively movable elements.

The invention is illustrated by the accompanying drawings wherein,

Figure 1 is a plan of the implement,

Figure 2 a side elevation thereof,

Figure 3 an alternative construction of a portion of Figures 1 and 2.

Figure 4 is an elevation of a portion of a detachable wheel, and

Figure 5 is a plan of Figure 4 showing in chain lines the implement in using position.

The implement is designed for moving to or from each other, two pins such as 16 and 10, Figures 4 and 5, fixed respectively on two relatively movable elements such as a nave member 11 and a hub member 13 of a detachable wheel.

This implement is so constructed that with a constant pull the tightening force available will increase gradually as required until a maximum tightening grip is obtained.

The implement consists of a hand lever 30 on the lower end of which is an eccentric sheave 31 having an eccentric hole 32. The eccentric sheave 31 fits in a strap 33 formed on one end of an eccentric strap member 34 operating as a connecting link and referred to herein as a connecting link 34, the other end of the link being provided with a hole 35.

The holes 32 and 35 are adapted to fit over

two members such as the pins 10 and 16 required to be brought together with a great force.

The connecting link 34 is provided with stops 37 and 38 for limiting the movement of the hand lever 30, the upper portion of the stop 38 being provided with a pusher or press button 47 to facilitate placing the implement on the pins 10 and 16.

When the implement is placed on the pins such as 16 and 10, and the eccentric sheave 31 turned by means of the hand lever 30 in the strap 33, the eccentric action of the hole 32 causes the pins 16 and 10 to move to or from each other relatively according to the direction of the movement of the hand lever 30 and the position of the centre of the eccentric sheave 31 relatively to a line passing through the centres of the pins 16 and 10, the tension increasing to a greater and greater extent between the pins as they approach each other to the position in which all three centres are in one straight line.

In designing the implement for use in tightening the detachable wheel shown in Figures 4 and 5, on its hub, the connecting link 34 is provided with a quadrant portion 36 having a projection 39 adapted to enter laterally into a groove 46 cut in the side of the pin 21. The projection 39 is formed by a plate secured to the link 34 by screws 58.

The groove 46 is normally covered by a sleeve or detent 18 and when the latter is depressed by placing the implement on the two pins 10 and 16 the groove 46 is uncovered so that when the hand lever 30 is moved to turn the connecting link 34 about the pin 16 in the wheel tightening operation the projection 39 slides in the groove 46 and so holds the tightening implement in position.

When the tightening is completed a notch 40 provided in the quadrant 36 comes into register with the pin 21 so that the projection 39 slides out of the groove 46 and leaves the tightening device free to be removed from the pins 16 and 10. The notch 40 may be so disposed on the projection 39 of the quadrant 36 that the tightening implement can only be put on or withdrawn from the pins 16 and 10 when the loose hub 13 is completely locked or unlocked, and the relative positions of the notch 40 and the groove 46 will then serve to give a visible and phys-

ical indication as to the wheel being locked or unlocked.

The sheave 31 is held in position in the strap 33 by making the portion 48 a detachable plate held on the main portion of the sheave 31 by screws 49, and instead of providing a notch 40 in the projection 39 of the quadrant 36, the projection 39 can be made to move radially inwards as shown in Figure 5 wherein the projection 39 is a plate provided with a pusher 50 from which extend two headed pins 51 and 52 sliding in a slot 53 provided in a plate 36 fixed on the link 34 by screws 54, the plate 39 having a pin 55 extending from its lower edge and sliding in a fixed lug 56, the pin 55 being provided with a spring 57 for keeping the plate 39 in the extended position so that it can be moved laterally into the groove 46 in the pin 21 as described in using the implement.

It will be evident that when the hand implement is applied to turn the loose hub 13, rotation of the crank lever 30 about the wheel pin 10 fitting in the hole 32 produces a relative motion between this pin and the loose hub pin 16 when in the hole 35 and consequently a rotation of the loose hub 13 in the wheel. For a uniform speed of rotation of the lever 30 the motion between the pins 10 and 16 is practically a simple harmonic one and (as is characteristic of slider crank chains, the velocity ratio between the crank pin, that is the eccentric sheave 31, and the slider, that is the loose hub pin 16, approaches infinity as a dead centre is approached. It is this characteristic which has been utilized in the invention for obtaining great leverage wherewith to very securely tighten the loose hub, for, as the loose hub becomes tighter the leverage becomes greater.

What I claim and desire to secure by Letters Patent is:—

1. A hand implement for effecting the relative movement of two elements, comprising an eccentric sheave and a connecting link, the sheave member being provided with means for rotating it about its axis and also with means for detachably connecting it to one of the relatively movable elements at a position eccentric to the sheave, and the connecting link forming a strap member of the eccentric and provided with means for detachably connecting it to the other relatively movable element.

2. A hand implement in accordance with claim 1 provided with means for preventing its removal from the two relatively movable elements during the operation of the implement.

3. A hand implement in accordance with claim 1, wherein means are provided for limiting the angular movement of the eccentric sheave.

4. A hand implement for effecting the relative angular movement of two elements about a common axis, comprising an eccentric sheave, a connecting link, an operating lever, means for detachably connecting one end of the link to one of the angularly movable elements, means for detachably connecting the eccentric sheave at a position eccentric thereto to the other angularly movable element, the sheave being rotatively mounted in the other end of the connecting link and fixed to the operating lever.

5. A hand implement for effecting the relative angular movement of two elements about a common axis each element being provided with a projecting pin movable to and from each other transversely, comprising an eccentric sheave, a connecting link, and an operating lever, one end of the connecting link having an opening to fit on the projecting pin of one of the movable elements, the eccentric sheave having a hole arranged eccentric to its axis and to fit on the projecting pin of the other movable element, the sheave being rotatively mounted in the other end of the connecting link and fixed to the operating lever.

6. A hand implement for effecting the relatively angular movement of two elements about a common axis one element being provided with two projecting pins and the other with one, all three pins being parallel to one another, comprising an eccentric sheave fixed to an operating lever, a connecting link having a projecting quadrant, and an operating lever, one end of the connecting link having an opening to fit on one of the projecting pins of one of the movable elements, the eccentric sheave having a hole arranged eccentric to its axis and to fit on the projecting pin of the other movable element, the sheave being rotatively mounted in the other end of the connecting link, and the projecting quadrant of the connecting link arranged during the operation of the implement to enter a groove provided in the side of the third pin projecting from one of the elements.

7. A hand implement for effecting the relative angular movement of two elements about a common axis one element being provided with a projecting pin having a groove in its side, comprising an eccentric sheave having an operating lever, a connecting link having a projecting quadrant, means for detachably connecting one end of the link to one of the angularly movable elements and means for detachably connecting the eccentric sheave at a position eccentric thereto to the other angularly movable element, the sheave being rotatively mounted in the other end of the connecting link, and the projecting quadrant of the connecting link arranged during the operation of the implement to enter a groove provided

in the side of the pin projecting from one of the elements.

8. A hand implement for effecting the relative angular movement of two elements about a common axis one element being provided with a depressible spring-retumed projecting pin having a groove in its side, comprising an eccentric sheave having an operating lever, a connecting link having a projecting quadrant provided at one portion with a notch, means for detachably connecting one end of the link to one of the angularly movable elements and means for detachably connecting the eccentric sheave at a position eccentric thereto to the other angularly movable element, the sheave being rotatively mounted in the other end of the connecting link, and the projecting quadrant of the connecting link arranged during the operation of the implement to enter a groove provided in the side of the pin projecting from one of the elements and move in such groove until it reaches the notch and so enable the spring controlled pin to rise in the notch.

9. A hand implement for effecting the relative angular movement of two elements about a common axis one element being provided with one fixed projecting pin and one depressible spring-retumed pin and the other with one pin all three pins being parallel to one another, comprising an eccentric sheave fixed to an operating lever, a connecting link having a projecting quadrant provided at one portion with a notch, and

an operating lever, one end of the connecting link having an opening to fit on one of the projecting pins of one of the movable elements, the eccentric sheave having a hole arranged eccentric to its axis and to fit on the projecting pin of the other movable element, the sheave being rotatively mounted in the other end of the connecting link, and the projecting quadrant of the connecting link arranged during the operation of the implement to enter a groove provided in the side of the depressible pin projecting from one of the elements and move in such groove until it reaches the notch and so enable the spring controlled pin to rise in the notch.

10. A hand implement for effecting the relative angular movement of two elements about a common axis each element being provided with a projecting pin movable to and from each other transversely, comprising an eccentric sheave, a connecting link, and an operating lever, one end of the connecting link having an opening to fit on the projecting pin of one of the movable elements, the eccentric sheave having a hole arranged eccentric to its axis and to fit on the projecting pin of the other movable element, the sheave being rotatively mounted in the other end of the connecting link and fixed to the operating lever the connecting link being provided with stops for limiting the movement of the operating lever.

In witness whereof I affix my signature.
WALTER VILLA GILBERT.
